UNITED STATES PATENT OFFICE.

PAUL BRIONES, OF BOLINAS, CALIFORNIA.

SHIP CONSTRUCTION.

1,076,624.

Specification of Letters Patent. Patented Oct. 21, 1913.

Application filed November 16, 1912. Serial No. 731,756.

To all whom it may concern:

Be it known that I, PAUL BRIONES, a citizen of the United States, residing at Bolinas, in the county of Marin and State of California, have invented new and useful Improvements in Ship Construction, of which the following is a specification.

This invention relates to the construction of ships, and it has for its object to so improve the construction that in the event of accidents, the ship shall be prevented from sinking, giving ample time for the debarkation of passengers and crew, and thus promoting the saving of life.

15 A further object of the invention is to construct a ship with an inner and an outer hull, said hulls being separated by a vacant space into which, in the event of damage to the outer hull, water may enter; means being 20 provided for the automatic discharge of such water, thereby keeping the ship afloat and minimizing danger to the passengers and crew.

With these and other ends in view which 25 will readily appear as the nature of the invention is better understood, the same consists in the improved construction and novel arrangement and combination of parts which will be hereinafter fully described 30 and particularly pointed out in the claims.

In the accompanying drawing has been illustrated a simple and preferred form of the invention, it being, however, understood that no limitation is necessarily made to the 35 precise structural details therein exhibited, but that changes, alterations and modifications within the scope of the claims may be resorted to when desired.

In the drawing,—Figure 1 is a side elevation of a ship constructed in accordance with 40 the invention. Fig. 2 is a longitudinal sectional view of the same. Fig. 3 is a transverse sectional view taken on the line 3—3 in Fig. 2. Fig. 4 is a sectional detail view 45 of one of the bumpers.

Corresponding parts in the several figures are denoted by like characters of reference.

In the construction of the improved ship two separate hulls are employed, namely, an 50 outer hull 1 and an inner hull 2. Said outer and inner hulls are joined together at their upper edges, as shown at 3. The bottom 4 of the inner hull is made substantially parallel to the bottom 5 of the outer hull, but 55 is spaced therefrom, as clearly shown in Figs. 2 and 3, the intervening space, 6, being

of any suitable dimensions. The sides and ends of the inner hull 2 are built at an angle to the sides and ends of the outer hull, being inclined in an inward direction with 60 respect to the inner hull, thus producing wedge-shaped spaces 7 entirely surrounding the sides and ends of the inner hull. Bumpers or buffers 8 are suitably arranged in the spaces 6 and 7 between the walls of 65 the inner and outer hulls for the purpose of strengthening and reinforcing the same. These bumpers may consist of blocks of rubber or other suitable resilient material, or they may consist of blocks a, b of wood or 70 other suitable material, slidably connected together by means of guide pins or dowels 9 and having springs 10 interposed therebetween, thus affording a resilient reinforcing construction. 75

The outer hull 1 is provided at a suitable distance above the water line with a plurality of ports 11 which are normally obstructed by means of closures, such as screw caps 12 which prevent water from entering 80 the spaces between the hulls by the wash of the sea or from other ordinary causes. Should a leak occur in the outer hull from any cause whatever, one or more of the closures 12 may be removed, and the water 85 entering between the inner and outer hulls may then be discharged, thus maintaining the buoyancy of the ship and preventing serious accident. At times when the weather is stormy and a heavy sea is going it may be 90 found necessary to make some additional provision for facilitating the escape of water through the port holes 11. To meet such emergency hose 15 of rubber or other flat flexible material is provided, the same having 95 means, such as screw threaded collars 16, whereby they may be connected with the threaded flanges 17 surrounding the port holes, as seen in Figs. 1 and 3. The hose or tube 15 is provided with a terminal float 180 18 having an outlet 19 which may be protected by an upwardly opening valve 20 to permit the water to escape without danger of backing through the hose. These devices, however, will be found necessary only when 105 the sea is heavy.

Having thus described the invention, what is claimed as new, is:—

1. A ship comprising an inner and an outer hull joined together at their upper 110 edges, the sides, ends and bottoms of said inner and outer hulls being spaced apart,

said outer hull being provided above the water line with port holes surrounded by threaded flanges, in combination with flexible ducts adapted to be detachably connected 5 with said threaded flanges, said ducts being provided with floats having discharge openings.

2. A ship comprising an inner and an outer hull joined together at their upper 10 edges, the sides, ends and bottoms of said inner and outer hulls being spaced apart, said outer hull being provided above the water line with port holes surrounded by

threaded flanges, in combination with flexible ducts adapted to be detachably connected 15 with said threaded flanges, said ducts being provided with floats having discharge openings, and outwardly opening valves for said openings.

In testimony whereof I affix my signature 20 in presence of two witnesses.

PAUL BRIONES.
